UNITED STATES PATENT OFFICE.

ROBERT RUDDY, OF MOUNT VERNON, ASSIGNOR TO THE NATHAN MANUFACTURING COMPANY, OF NEW YORK, N. Y.

LUBRICATOR.

SPECIFICATION forming part of Letters Patent No. 334,679, dated January 19, 1886.

Application filed November 23, 1885. Serial No. 183,702. (No model.)

To all whom it may concern:

Be it known that I, ROBERT RUDDY, of Mount Vernon, in the county of Westchester and State of New York, have invented a certain new and useful Improvement in Lubricators, of which the following is a specification.

My invention is directed to lubricators of the class known as "sight-feed" lubricators, and intended more particularly for use with locomotives.

In running locomotives it sometimes happens that the sight-feed glass of the lubricator is accidentally broken. In any such case it is necessary to shut off the lubricator in order to prevent the discharge of steam and oil through the broken glass. In most instances it is difficult, if not indeed impossible, in event of such an accident to replace the glass during the run of the engine, and thus the engineer is left without practicable means of oiling the engine valves and cylinders.

It is the object of my invention to provide for these contingencies, and this I do by combining with the lubricator proper a simple and effective ancillary oiler, forming part of the lubricator, but in its action independent of and separate from said lubricator.

I am aware that in a general way it has heretofore been proposed to so construct and arrange lubricators—particularly sight-feed lubricators—as to provide means by which the oiling might be effected even though the main lubricator should become damaged or incapacitated for work. I do not therefore lay claim, broadly, to this feature.

My invention consists in the special means, hereinafter described, whereby I attain the result I have in view.

The nature of the invention and the manner in which the same is or may be carried into effect will be readily understood by reference to the accompanying drawings, in which—

Figure 1 is a vertical section of a lubricator embodying my improvement, the section being taken on line 1 2 3, Fig. 3. Fig. 2 is a side elevation of the same, looking in the direction of the arrow in Fig. 3. Fig. 3 is a horizontal section of the same on line 5 5, Fig. 1. Fig. 4 is a like section on line 4 4, Fig. 1, omitting the steam-valve and waste-cock.

The improvement is particularly designed

for and adapted to that kind of lubricator described in Letters Patent No. 316,834, of April 28, 1885, and No. 324,339, of August 11, 1885.

The lubricator shown in the drawings, except as to the new feature introduced into it, is similar in construction and arrangement to the lubricator shown and described in the Letters Patent last above named.

F is the oil-chamber of the lubricator; A, the main steam-conduit; B, the vertical steam-channel; C, the condenser; D, the extension of channel B. H J K L are the parts by which the water of condensation is fed from the condensing-chamber to the oil-chamber. E is the sight-feed glass. G P O are the sight-feed glass connections. N is the oil-feed pipe leading from the upper part of the oil-chamber to the lower connection, O, and I is the nozzle. All of these parts are arranged together and operate in the manner described with reference to the like-lettered parts in Patent No. 324,339, and they therefore require no further explanation here. The lubricator, like the patented device, is provided with a steam-valve, S, and a waste or draw-off cock or valve, T.

I now proceed to describe the improvement which I have added to the lubricator. I provide a small auxiliary oil-cup, a, provided with a neck or stem, which screws into the side wall of the lubricator and communicates, through its channel n, with the channel e, cast in the body of the lubricator, and from channel e continues a channel, f, drilled in the solid metal of the shank or stem of the lubricator, so as to open into the steam-conduit A at a point below or beyond the steam-valve S. It will thus be seen that this auxiliary oiler, while forming part of the lubricator structure, has no communication with the operative parts of the sight-feed lubricator, is not in any sense dependent thereon for its efficiency, but is entirely independent of and separated from the same, having its own supply of oil and its own independent access to the steam-conduit. Consequently the steam, water, and sight-feed valves can be operated without in any way affecting the auxiliary oiler. The oil-cup a, provided with a tubular internally - screw-threaded socket, b, in which screw the valve c, controlling openings m, which put the interior of the oil-cup in communication with the

channel n , has the form and construction of the ordinary tallow-cup, well known to every engine-driver; and its adaptation to the special purpose for which it is here intended therefore affords the simplest and safest means of auxiliary oiling, should the engine be temporarily deprived of the use of the lubricator proper. The auxiliary oiler might be differently located—as, for instance, it might be screwed directly into the shank or stem of the lubricator below or beyond the steam-valve; but I prefer the arrangement shown as being on the whole the most compact and convenient.

Having described my improvement and the best way known to me of carrying the same into effect, what I claim, and desire to secure by Letters Patent, is—

1. A sight-feed lubricator provided with an auxiliary oiler of the described form and construction screwed into the lower part of the lubricator and communicating by its own separate

and independent channel with the steam-conduit at a point below or beyond the steam-valve.

2. A sight-feed lubricator having the independent channel $e f$, located as described, and provided with the auxiliary oiler a , as and for the purposes hereinbefore set forth.

3. A lubricator having the oil and condensing chambers $F C$, the steam channel B , and the steam-conduit A , and provided with an auxiliary oiler and a channel therefor independent of and separate from the channel B , but communicating also with the steam-conduit A , as and for the purposes hereinbefore set forth.

In testimony whereof I have hereunto set my hand this 14th day of November, 1885.

ROBERT RUDDY.
